UNITED STATES PATENT OFFICE.

CHARLES DE QUILLFELDT, OF AMITYVILLE, NEW YORK.

BOTTLE-STOPPER.

SPECIFICATION forming part of Letters Patent No. 610,721, dated September 13, 1898.

Application filed June 10, 1898. Serial No. 683,048. (No model.)

To all whom it may concern:

Be it known that I, CHARLES DE QUILLFELDT, a citizen of the United States, residing at Amityville, in the county of Suffolk 5 and State of New York, have invented certain new and useful Improvements in Bottle-Stoppers, of which the following is a specification.

This invention relates to an improved bottle-stopper of that class which is intended to be used in bottling carbonated liquids.

The object of the invention is to adapt the well-known "Lightning" bottle-stopper, for which Letters Patent were granted to me on January 5, 1875, reissued June 5, 1877, No. 15 7,722, for use in bottling carbonated liquids in the ordinary bottles in which such liquids are put up. For this purpose it is necessary that in place of a pivotal connection of the 20 bail or yoke of the lever-frame with the stopper a detachable connection be employed, so that the stopper can be removed from the lever-frame, placed in the bottling-machine, and transferred to the mouth of the bottle by 25 the plunger of the bottling-machine when the bottle is filled with the carbonated liquid, after which the connection with the bail is established and the stopper locked in the well-known manner.

30 The invention consists, primarily, of a bottle-stopper having a pivoted bail and a locking-lever for the same, said bail being provided with a U-shaped upper portion adapted to engage the recessed shank of the stopper-head whenever the stopper is applied to the bottle.

The invention consists, secondly, in the peculiar construction of the bail by which the detachable connection of the lever-frame with 40 the stopper is accomplished, and, lastly, of a bottle-stopper the head of which is provided with a recessed shank of sufficient height to permit the application of the bail of the lever-frame of the device.

45 In the accompanying drawings, Figures 1 and 2 represent side elevations of my improved bottle-stopper, showing the same, respectively, in closed position on the mouth of the bottle and in the act of applying the bail 50 to the stopper and showing in dotted lines the stopper removed from the bottle-mouth and supported in the bail. Figs. 3 and 4 are

respectively a side elevation and a vertical central section of my improved stopper detached from the bail. Fig. 5 is a rear elevation of my improved bottle-stopper with the stopper detached; and Fig. 6 is a plan view of the same, partly in horizontal section, through the stopper-head.

55 Similar letters of reference indicate corresponding parts.

Referring to the drawings, A represents a bottle such as is usually employed in bottling carbonated liquids.

B is the stopper, which is formed of a tapering lower portion or neck upon which is placed a rubber gasket, said gasket being thickened at its upper end. A shoulder b is formed on the lower end of the neck of the stopper B, said shoulder b retaining the elastic 65 gasket in position on the neck of the stopper. Above the stopper-neck is the head B' of the stopper, which has a cylindrical shank d', of smaller diameter than the cylindrical head, as shown in Figs. 3 and 4. The recessed shank d' is of sufficient height to permit the 70 free application of the bail of the wire lever-frame to the head of the stopper whenever required. The lever-frame consists of the usual wire neck-band e and a U-shaped locking-lever E, that is pivoted to eyes of the neck-band and provided with eyes for the inwardly-bent ends of the bail E'. The wire neck-band, the locking-lever, and the bail or yoke, which serve for retaining the stopper 75 in the mouth of the bottle, are all of the well-known construction and form no part of the present invention, with the exception of the bail, the upper transverse portion E² of which is bent in approximately U shape, as shown 80 in Fig. 6, so as to be applied detachably to the shank of the stopper. The legs of the U-shaped portion E² converge somewhat and contact with the shank of the stopper near their outer ends and by their pressure hold 85 the shank of the stopper in contact with the rear portion of the U-shaped portion and prevent its escape and entire disconnection from the lever-frame. The device is not rigid, however, but is made from wire having 90 more or less tension, whereby the U-shaped gripping portion yields at the points f f, thereby permitting the removal of the stopper from the lever-frame when sufficient 95 100

- force is applied. The **U**-shaped portion E^2 then immediately springs back into its former shape, and force has to be again employed when it is desired to insert the stopper. The 5 stopper having once been inserted, it is gripped with sufficient strength to hold it against the shocks of ordinary use and is only intended to be removed when the bottle is placed in the bottling-machine for refilling. 10 In forming the upper transverse portion of the bail the wire is first bent forward and then backward, forming the short forward bends $c c$, one at each side of the **U**-shaped portion. 15 As shown in Figs. 1 and 2, the bends of the gripping portions are made at right angles to the side portions of the bail E' . By this construction the entire **U**-shaped portion E^2 is adapted to lie flat upon the shoulder B' of the 20 stopper when the stopper is inserted in the bottle, thus making a perfectly tight closure for the bottle.
- When it is desired to bottle carbonated liquids into bottles having my improved bottle- 25 stopper, the stoppers are detached and fed into a guide-tube of the bottling-machine. The thickened rims of the gaskets are frictionally guided in said tube. As soon as the bottle is filled with the carbonated liquid the 30 plunger of the machine forces the stopper onto the mouth of the bottle. At the same time the operator forces the **U**-shaped portion of the bail over onto the shank of the stopper-head, as shown in Fig. 2, and then 35 moves the locking-lever in downward direction, so as to produce the tight closing of the bottle-stopper on the mouth of the bottle. By the construction described the well-known "Lightning" bottle-stopper can be applied 40 successfully for bottling carbonated liquids, which heretofore could not well be done.

When the bottle is to be opened, the stopper is removed from the mouth of the bottle in the usual manner by releasing the lock-

ing-lever and held by the retaining-bail, as 45 shown in dotted lines in Fig. 2, until the same is returned for refilling, when the stopper is detached from the bail preparatory to filling.

Having thus described my invention, I claim as new and desire to secure by Letters 50 Patent—

1. The combination of a locking-lever pivoted to the neck of the bottle, a bail pivoted to eyes of said lever, said bail being provided in its upper transverse portion with an approximately **U**-shaped portion having converging legs, and a stopper provided with an elastic gasket at its lower portion and a recessed shank in its head, which shank is adapted to be detachably engaged between 60 said converging legs and the base of said **U**-shaped portion of the bail, substantially as set forth.

2. In a bottle-stopper, a bail for engaging the stopper-head, provided in its upper transverse portion with short forward bends and an approximately **U**-shaped portion having converging legs between said bends, substantially as set forth.

3. A bottle-stopper, comprising a locking- 70 lever applied to the neck of the bottle, a bail connected with said locking-lever and provided with an approximately **U**-shaped transverse upper portion, and a stopper adapted to be detachably engaged by said bail and to 75 permit the tilting of said transverse portion relatively to said stopper, whereby the stopper may be removed from the bottle-mouth without disengaging said bail therefrom, substantially as set forth.

In testimony that I claim the foregoing as my invention I have signed my name in presence of two subscribing witnesses.

CHARLES DE QUILLFELDT.
